Patented Aug. 24, 1915.

UNITED STATES PATENT OFFICE.

MARVIN W. SINGER, OF CHICAGO, AND DANIEL WOODHEAD, OF EVANSTON, ILLINOIS.

LIGHTING-FIXTURE.

1,150,894.

Specification of Letters Patent. Patented Aug. 24, 1915.

Application filed November 19, 1913. Serial No. 801,802.

To all whom it may concern:

Be it known that we, MARVIN W. SINGER, residing at Chicago, in the county of Cook and State of Illinois, and DANIEL WOODHEAD, residing at Evanston, in the same county and State, both citizens of the United States, have invented a certain new and useful Improvement in Lighting-Fixtures, of which the following is a specification.

Our invention relates to electric lighting fixtures, particularly for passenger cars and other situations where the fixtures are supported from a ceiling or side wall.

It will be understood by those who have had experience in installing electric lighting fixtures that a good deal of inconvenient work is usually entailed in making the final connection between the supply wires and the fixture wires. The usual method is to fish the end of the supply wires through from the ceiling or conduit and then electrically splice these wires to the fixture wires, subsequently replacing the insulation and finally slipping a loose canopy up to the ceiling to cover up the unsightly connections. This usually involves overhead work and in many cases requires the simultaneous efforts of at least two men, one holding the fixture while the other makes the electrical connection.

The object of our invention is to avoid these difficulties and inconveniences and to provide a construction such that the electrical connections may be made by a single operator without assistance, after the fixture is hung in place, and also to render it possible to accomplish a neat and workman-like job and incidentally a connection which may be made and re-made as many times as desired without damaging the ends of the wires.

It is also our object to provide means for definitely holding the ends of the wires and insulating them from surrounding objects.

We accomplish our objects by the mechanism illustrated in the accompanying drawings in which—

Figure 1 is a general side elevation of a fixture embodying our invention. Fig. 2 is a vertical section of the fixture and connections taken on the line 2—2, Fig. 3. Fig. 3 is a bottom plan section taken on the line 3—3, Fig. 2.

Similar numerals refer to similar parts throughout the several views.

As the invention is well adapted for passenger car construction we have elected to show the invention in connection with a car roof. In the drawings, the lower panel of the car roof 1 has an opening 2 through which the feed wires 3 pass. Beneath the outer opening 2 is fastened a plate 4 consisting usually of metal. It is secured to the car roof by screws 5 or other suitable fastening devices. The pending parts of the fixture may assume various forms, the present design showing three arms 6 supporting a bowl or shade 7. In the illustration shown in Fig. 1, the bowl is inverted and contains the lamp 8 on the inside, thus producing what is known as "indirect lighting". The shape and arrangement of the bowl or shade, however, are immaterial.

In the design selected to illustrate the invention, the ceiling plate is circular in outline and dished in such manner that it contacts with the car roof at its periphery, but at its central portion affords space for the terminal plate 9. This plate is preferably located symmetrically under the outlet opening 2 in the car roof and consists of slate, fiber, asbestos board or other suitable material.

The ceiling plate is apertured at the bottom, preferably in the center, directly beneath the outlet opening 2. A cover 10 is provided for normally holding this opening closed, the cover being removably held in place by screws 11 or other convenient fastening means.

In the most desirable form of the invention, the terminal plate carries four binding posts 12, 13, 14 and 15. These posts are connected in pairs by any suitable conductors 16, 17. The conductors 16, 17 are located on top or back of the plate while the heads of the terminals are on the bottom where they are accessible through the opening 4a of the ceiling plate. The feed wires 3 are led down through an aperture 9a in the terminal plate and hence their ends are in convenient position to be connected to and disconnected from one pair of binding posts, 14, 15. The fixture wires 18 are passed preferably down through one of the arms 6 to the lamp 8 as shown at the left part of Fig. 2. An eyelet 19 of insulating material is provided in the ceiling plate 4 in convenient position so

that the ends of said wires may be connected to the lower end of the remaining binding posts, 12, 13. Thus it will be seen that the loose ends both of the feed wires and of the fixture wires can be attached to the binding posts on the lower side of the terminal plate where convenient access is afforded to the electrician. As a result, a single electrician, unassisted, may make all the connections 10 simply with the aid of a screw driver.

In operation, the ceiling plate 4 carrying with it the terminal plate 9 and pendent parts of the fixture including the arms 6, bowl 7 and lamp 8 and fixture wires 18 is 15 secured to the car roof by any ordinary mechanic. The jumper wires 16, 17 have been previously set in place and the ends of the feed wires 3 will be fished through the terminal plate before the ceiling plate is 20 finally fastened. When the electric connections are to be made, the electrician simply passes the ends of the fixture wires 18 up through the eyelet 19 and fastens the ends to the binding posts 12, 13. He also connects the ends of the feed wires 3 to the binding posts 14, 15. This, it will be noted, can easily be done through the central aperture 4^a in the ceiling plate and nothing more than an ordinary screw driver is required. As soon as these connections of the feed wires and the fixture wires to the 30 respective binding posts are completed, the fixture is ready for use. The electrician then fastens the cover 10 in place and the work is finished.

The operation of connecting the feed wires and fixture wires is so simple that the skill of an electrician is hardly required. No soldering or wrapped joints are neces-

sary and the work may easily be done by a 40 workman having little knowledge of electricity. As the terminal plate 9 supports all the terminal connections and holds them at a distance from the surrounding objects, the construction is a very safe one and practically eliminates the danger of short circuits or crossed wires. Another advantage 45 of our construction lies in the fact that the connections may be inspected at any time by simply removing the cover 10. It will 50 be noted that in our construction the weight of the fixture is carried by the roof itself and not by any conduit or feed wire pipes as is frequently the case in lighting fixture 55 construction.

Having thus described our invention, what we claim as new and desire to secure by Letters Patent is:

In a lighting fixture, the combination of a downwardly dished ceiling plate, pendent 60 parts secured to said plate, a terminal block of insulating material located in the dished portion of said plate, binding posts mounted in said terminal plate and electrically connected together in pairs, the heads of 65 the binding posts being located on the under side of the terminal plate for connection to the feed and fixture wires, said ceiling plate having an aperture near the binding posts 70 for affording access to them.

In witness whereof we have hereunto subscribed our names in the presence of two witnesses.

MARVIN W. SINGER.
DANIEL WOODHEAD.
